US0D1063625S

(12) **United States Design Patent** (10) Patent No.: **US D1,063,625 S**
(45) Date of Patent: ** Feb. 25, 2025

(54) **BOTTLE**

(71) Applicant: **POLMOS ZYRARDOW SPOLKA Z OGRANICZONA ODPOWIEDZIALNOSCIA**, Zyrardow (PL)

(72) Inventor: **Ivan Bell**, London (GB)

(73) Assignee: **POLMOS ZYRARDOW SPOLKA Z OGRANICZONA ODPOWIEDZIALNOSCIA**, Zyrardow (PL)

(**) Term: **15 Years**

(21) Appl. No.: **35/517,938**

(22) Filed: **May 5, 2023**

(80) **Hague Agreement Data**

Int. Filing Date: **May 5, 2023**

Int. Reg. No.: **DM/230436**

Int. Reg. Date: **May 5, 2023**

Int. Reg. Pub. Date: **Jul. 28, 2023**

(51) LOC (15) Cl. **09-01**

(52) U.S. Cl.

USPC **D9/566**
